UNITED STATES PATENT OFFICE

JAMES A. CAMERON, OF BROOKLYN, NEW YORK, ASSIGNOR TO CAMERON MACHINE COMPANY, OF BROOKLYN, NEW YORK, A CORPORATION OF NEW YORK

MAKING BACKING MEMBER FOR SLITTING MACHINES

Application filed May 25, 1928. Serial No. 280,516.

This invention relates to a method of making a backing member for a slitting machine such as is disclosed in application Ser. No. 332,037, filed January 12, 1929.

5 Machines for slitting webs of flexible material are now required to act on webs of very considerable width, and in machines that employ the "score-cut" method (involving the use of a smooth-face "glass-hard" backing member and a blunt cutting member) the weight and length of the backing member present unusual difficulties not only in the process of manufacturing such member but also in maintaining the proper running balance at high speeds,—this, quite aside from the question of expense.

The main object and feature of this invention is to devise a method of producing a backing member that, while possessing the requisite rigidity and hardness, will nevertheless be of less weight, easier to make and cheaper to manufacture than backing members now employed in this type of machine.

In the accompanying drawings the invention is disclosed in several concrete and preferred forms in which:

Fig. 1 is a diagrammatic view showing the step of bending a flat blank of sheet material into circular form.

20 Fig. 2 is a sectional view substantially on the plane of line 2—2 of Fig. 3 showing the curved blank of Fig. 1 in position on a mandrel during the step of welding the free ends thereof to produce a sleeve.

25 Fig. 3 is a sectional view substantially on the plane of line 3—3 of Fig. 2.

Fig. 4 is a diagrammatic view of a crucible to denote the steps of hardening the blank.

30 Fig. 5 is a view similar to Fig. 2 but showing the step of grinding the outside of the sleeve.

Fig. 6 is a diagrammatic view showing the step of grinding the inside of the sleeve.

Fig. 7 shows the sleeve mounted on a core of softer material than itself.

35 Fig. 8 is a diagrammatic view showing a flat blank of sheet metal drawn up into cup-shape.

Fig. 9 is a diagrammatic view showing the 40 cup-shape blank converted into a sleeve.

In brief, the process consists of converting a flat blank of sheet metal into a sleeve, then hardening said sleeve, then grinding said sleeve inside and outside, and then mounting said sleeve on a core of softer material than itself. The steps for carrying out this process may vary but a preferred method is shown in Figs. 1 to 7 inclusive. As there shown, a flat blank 1 of sheet metal, is subjected to the action of rollers 2 to bend it into circular form. The blank so produced may now be placed upon a collapsible mandrel 3 and held in place by clamping bands 4 adapted to be tightened by adjustable screws 5. The action here is that the free ends of the curved blank are brought, preferably, into butting engagement and are then welded by electric welding or otherwise. After the weld has been made, the mandrel is collapsed in a well-understood manner and the sleeve is removed. Fig. 4 shows the step of hardening the sleeve. This is represented here by the representation of crucible 6 and will, of course, vary in accordance with the character of the material acted upon and the degree of hardness desired. One method is to place sleeve 1 in crucible 6, provided with cover 7, and to carbonize it and cool it. After this, sleeve 1 is again heated and may be quenched in oil, brine or plain water. Sleeve 1 is now again mounted on a mandrel as 8 (Fig. 5) and subjected to the action of grinding element 9 that grinds the outside of the sleeve. The sleeve thus ground on its outside is now placed in workholder 10 (Fig. 6) and sleeve 1 is subjected to the action of grinding element 11 that grinds the interior of the sleeve. The sleeve thus finished can now be placed upon a core 12 (Fig. 7) softer than itself, and it will be understood that any number of sleeves as 1 can be placed upon such core member. Preferably sleeve 1 is rotatable on the core.

By the foregoing method it will be evident, that the weight of the parts of the slitting machine are reduced and the process of manufacture is less expensive than heretofore, and that this can be done without sacrificing strength or qualities of hardness.

In Figs. 8 and 9 is shown an alternate form

of a method of converting a flat blank of sheet metal into sleeve form. As there shown a flat blank is placed in a drawing press, the plunger of which latter is indicated at 13, and the blank is drawn into a cup-shape blank 14. This blank is then trimmed to produce a sleeve 1 by means of shears or cutting members as will be understood. The remaining steps of the process may then be as previously described in connection with 10 Figs. 2, 3, 4, 5, 6 and 7.

I claim:

1. The method of making a backing member for a slitting machine which consists in converting a flat blank of sheet metal into 15 a sleeve, then hardening said sleeve, then grinding said sleeve inside and outside, and then mounting said sleeve on a core of softer material than itself.
2. The method of making a backing member for a slitting machine which consists in drawing a flat blank of sheet metal into cup-shape form, then trimming the drawn blank to produce a sleeve, then hardening the sleeve, then grinding said sleeve inside and outside, 25 and then mounting the sleeve on a core of softer material than itself.
3. The method of making a backing member for a slitting machine which consists in converting by bending a flat blank of sheet 30 metal into sleeve form, then hardening said sleeve, then grinding said sleeve inside and outside, and then mounting said sleeve on a core of softer material than itself.

35 Signed at the borough of Brooklyn, in the county of Kings, city and State of New York, this 21 day of May, 1928.

JAMES A. CAMERON.
